Primary Examiner — Philip S Hyder*Assistant Examiner* — Cary M Robinson(74) Attorney, Agent, or Firm — Banner & Witcoff, Ltd.(57) CLAIM

The ornamental design for a display screen with graphical user interface, as shown and described.

DESCRIPTION

FIG. 1 is a front view of a display screen with graphical user interface showing my new design; and, FIG. 2 is a front view of a display screen with graphical user interface showing an alternative embodiment of my new design.

The outermost broken line illustrates the display screen, and the remainder of the broken lines, including the broken line showing of alphanumeric characters and envelope, illustrate portions of the graphical user interface. None of the broken lines form part of the claimed design.
